[57] CLAIM

The ornamental design for a fireplace screen, as shown and described.

DESCRIPTION

FIG. 1 is a front elevational view of a fireplace screen showing my new design;

FIG. 2 is a top plan view thereof;

FIG. 3 is a left side elevational view thereof;

FIG. 4 is a right side elevational view thereof;

FIG. 5 another front elevational view thereof showing the doors in an open position;

FIG. 6 is a top plan view of a second embodiment thereof;

FIG. 7 is a left side elevational view thereof;

FIG. 8 is a right side elevational view thereof; and

FIG. 9 is a front elevational view thereof.

The broken line disclosure of a fireplace in FIG. 1 is for illustrative purposes only and forms no part of the claimed design.
